UNITED STATES PATENT OFFICE.

NOBUCHIKA SUGIMURA, OF TOKYO, JAPAN, ASSIGNOR TO GENERAL ELECTRIC COMPANY, A CORPORATION OF NEW YORK.

ELECTRICAL APPARATUS.

1,394,951.

Specification of Letters Patent. Patented Oct. 25, 1921.

Application filed June 5, 1919. Serial No. 301,959.

To all whom it may concern:

Be it known that I, NOBUCHIKA SUGIMURA, a subject of the Japanese Empire, and resident of Tokyo, Japan, have invented 5 certain new and useful Improvements in Electrical Apparatus, of which the following is a specification.

My invention relates to tanks or containers for electrical apparatus, which are 10 customarily made of sheet metal. The general objects of my invention are to improve the construction of such tanks, to produce a strong and durable tank which may be subjected to severe weather conditions without 15 being affected by corrosion, and to reduce the cost of construction, transportation and installation of such tanks.

In the construction of electrical apparatus which is designed to be cooled artificially 20 such for instance as transformers, some induction regulators and the like, the tanks or containers for such apparatus must be sufficiently strong mechanically to support not only the apparatus itself but also the 25 weight of the cooling medium that is contained in the tank. This has resulted in bulky and rather heavy tanks which are expensive both to manufacture, transport and install. As an alternative to this it has been 30 suggested to make such tanks of a plastic such as concrete, which may be constructed at the place of installation, but the difficulties to be overcome in making the plastic, especially concrete, oil tight and proof 35 against osmosis has heretofore offset substantially all the advantages naturally attendant on the use of such plastic.

In the practice of my invention, I have combined both the use of sheet metal and 40 plastic construction in a novel manner which yields a construction embodying substantially the combined advantages of each material. The trunk or walls of the tank which are subject only to hydrostatic side 45 thrust of the oil or insulating fluid within are accordingly made of sheet metal which affords good radiation, while the base which is subject to severe compressional strains is made of the plastic, which is preferably reinforced; the interior surface being made 50 proof against osmosis by one or another of the novel coöperating arrangement of parts hereinafter more fully set forth.

Further objects and advantages of my invention will appear from the following de-

tailed description when taken in connection with the accompanying drawings in which:

Figure 1 shows a view partly in section and partly in elevation of a tank for use in connection with transformers constructed to 60 embody my invention. Fig. 2 is a similar view of another form of tank differing from that shown in Fig. 1, constructed in accordance with my invention. Fig. 3 is a cross section through the plastic base of the tank 65 shown in Fig. 2; while Figs. 4, 5 and 6 show further modified constructions.

Referring now to the drawing, and to Fig. 1 in particular, 10 denotes the trunk or side walls of the tank for the transformer 11, 70 shown as submerged in the oil or other cooling medium 12 contained in the tank. The high and low tension leads for the transformer are shown at 13 and 14 respectively and are shown as brought out through the 75 cover of the tank in a convenient conventional manner.

The trunk 10 is made of sheet material, preferably mild steel plate, having its edges secured in any convenient manner, as by 80 riveting or welding, so as to give it a cylindrical form. This trunk is secured in a molded base 15 made of plastic material, preferably concrete, although any suitable plastic may be used, as for instance, asphalt, 85 cement, fibrocement and the like. This plastic base 15 is preferably reinforced as shown by the means of a metallic lattice or screen 16 and a plate or rods 17. The lower rim of the trunk 10 is shown as distended in 90 order to be more securely held in place by the plastic 15; the latter being so formed as to engage a considerable portion of the lower surface of the trunk both interiorly and exteriorly.

In order to make the plastic base 15 proof 95 against osmosis, the inner surface of the base, which is exposed to the liquid 12 is covered with a sheet 18 of thin metal. This sheet 18 is made to fit intimately the configuration of the interiorly exposed surface of the base and at its outer edge tightly abuts against the sides of the trunk 10.

The trunk without the base would generally be shipped to the place where the transformer is to be used, since suitable plastic material for the base can, as a rule, be readily obtained at the place of installation.

At the place of installation the base 15 would accordingly be shaped in suitable 110

molding forms, the trunk put in place and the whole left to set; after which the transformer itself would be put in place and then the proper amount of insulating fluid 5 added to the content of the tank.

In Figs. 2 and 3, is shown a corrugated trunk 20, the corrugations affording a greater radiating surface than is afforded by the plain surface of the trunk shown in Fig. 1. 10 The trunk 20 affords a housing for electrical apparatus indicated at 21 whose terminal leads are shown at 22. A plastic base 23 is here shown as reinforced by the lattice 24. Instead of the trunk 20 being inserted 15 in the base 23 as it is left to set, the base 23 is shown as formed with a shallow pit 25 in its top surface; the sides and bottom 20 of the pit being preferably faced with suitable material indicated at 26. The upper edge of the pit is shown as reinforced by 25 the wire or cable 27 passing around its periphery.

The lower end of the trunk 20, which is here shown as provided with an auxiliary 25 bottom 28 of suitable material such as treated pressboard is inserted in this pit and an adherent water proof filling material 29 such as lead is inserted in the interstices around the edge of the pit 25.

30 In Fig. 4 I have illustrated how I may make the base 43 for the trunk 40 impervious to oil or proof against osmosis in still another manner. Here instead of a thin metal sheet intimately fitting the configuration of the interiorly exposed surface of the base, I have used an asphalt cloth 45, though obviously any layer of impervious material so associated with the base may be used. The edges of the cloth 45 are 40 shown as bent down at 46 to make a snug engagement with the wall of the trunk 40.

In Fig. 5 I have shown still another construction for making the base proof against osmosis. Here a thin auxiliary base of 45 sheet metal 51 is welded to the trunk 50 and the whole set in the plastic base 53 which is shown as preferably reinforced. Plastic material in this form of my invention engages with the auxiliary base 51 both 50 interiorly and exteriorly.

In Fig. 6 I have illustrated still another

form of impervious base construction for the trunk 60 which is set in plastic base 63. The interiorly exposed surface of the base 63 is here made proof against osmosis 55 by a suitable surface treatment, which may be accomplished by a suitable coating of water-proof varnish. The interstices which may exist about the joint between the wall of the trunk and the plastic material of the 60 base are here also filled preferably with a lead packing which may be applied in molten condition.

The top rim for the tank may also be formed of plastic as shown at 66 which 65 may be set in any desired form by suitable molds and is preferably reinforced as shown at 67.

While I have here shown and described several embodiments of my invention which 70 are, at present, the best means known to me for carrying the same into effect, I would have it understood that they are merely illustrative and that I do not mean to be limited thereby to the precise details shown, 75 nor in the choice of equivalent arrangements except as defined in my claims hereunto annexed.

What I claim as new and desire to secure by Letters Patent of the United States, is: 80

1. In a casing for liquid submerged electrical apparatus, the combination with a trunk constructed of sheet metal, of a plastic base formed to engage with a rim of said trunk, and a thin metallic surface overlying 85 the interiorly exposed surface and the edge of the plastic about the rim of said trunk adapted to render the same impervious to the liquid in the casing.

2. In a casing for liquid submerged electrical apparatus, the combination with a trunk constructed of sheet metal, of a plastic base formed to engage with a rim of said trunk, reinforcing material embodied in said base, and a liquid tight surface material intimately associated with said plastic for making its interior surface and the rim about said tank proof against osmosis. 95

In witness whereof, I have hereunto set my hand this sixth day of May, 1919.

NOBUCHIKA SUGIMURA. [L. s.]
